BOTTLE WASHING MACHINE

George Volkert, Superior, Wis.

Application November 24, 1937, Serial No. 176,211

2 Claims. (Cl. 15—95)

This invention relates to bottle washing devices and has for its principal object simplicity of construction as well as operation.

A further object is that of providing convenient means for both washing and rinsing either by steam or water and with or without a detergent or other washing compound, and at the same time providing simple means for such together with it being optional with the operator 10 to rinse or wash with any other preferred compound.

Another object is to provide means whereby to insure an equal amount of detergent being supplied to each bottle or receptacle being 15 washed.

Still other objects and advantages of the invention will appear in the following description thereof.

Referring now to the accompanying drawings, 20 forming part of this application, and wherein like reference characters indicate like parts:

Figure 1 is a combined central section and elevation of a washing unit embodying the invention.

Figure 2 is a plan view of one of the complete devices partly broken away.

Figure 3 is an enlarged sectional view of the water, steam, and standpipe control connection.

Figure 4 is a similar view of the automatic 30 check valve in the standpipe.

Figure 5 is a central sectional view partly in elevation of a modified form of mixing or distributing chamber, and

Figure 6 is a fragmental top plan view of Fig. 35 5, with a portion of the cover of the distributing chamber removed.

In the drawings the numeral 1 represents a comparatively shallow and conveniently shaped base receptacle into which are shown as installed through one end the water supply pipe 2 and through the opposite end the steam supply pipe 3; these pipes meeting within the center of the receptacle 1 and connected by the three-way valve 4, the centrally disposed outlet 5 of which is connected to and disposed within the enlarged coupling 6 attached to the lower end of the standpipe 7 extending upwardly through and centrally of the elongated rectangularly shaped housing 8, supported in any desired manner above the pipes 2 and 3 within the receptacle 1. Centrally of and within this housing 8 is formed a receptacle 9, having an arcuately shaped bottom 10 therein and supported in any desired manner within the receptacle 1. Within the receptacle 9, 55 the standpipe 7 has surrounding same a platform

11 for convenient support of the upper end of four slightly inclined water circulating pipes 12, which extend downwardly and through the arcuate bottom 10 of the receptacle 9, and are each connected with a branch pipe 13, there being four of same extending radially from the siphon coupling 6 for such connection. Intermediate of the coupling 6 and the attachment to the pipes 12 are installed in each of said branch pipes 13 a second pipe connection 14 extending upwardly 10 and through the arcuate bottom 10 communicating with the chamber 9, and the openings to which are controlled as by the sliding gate like members 15, the handles of which correspond in shape to the arcuate bottom and extend upwardly and beyond the ends of the receptacle 9, as at 16, providing convenient handles for manipulation of the gates 15 and thereby governing the amount of detergent from the receptacle 9 entering the pipes 14, or to prevent any of said 20 detergent from passing thus into the coupling 6 as desired, it being noted that each member 15 controls two of the openings into the pipes 14. By this connection it will be noted that as the level of water within the receptacle 9 has risen 25 above the platform 11 a portion thereof at least will circulate downwardly through the pipes 12 into the coupling 6, and if the water should rise materially above said platform a suitable number of holes 37 are provided through the 30 side walls of the receptacle 9 and through which such excess water is cared for, and any form of drain pipe, not shown, from the base receptacle 1, may obviously be installed to care for same.

Upon the standpipe 7 and a suitable distance 35 above the receptacle 9 is installed a novel form of T-like coupling 17, shown as carrying an automatically controlled check valve therein, which will be described later, and the opposed horizontally disposed connections of the T have branch 40 pipes 18 installed therein. Each of these branch pipes is shown as carrying three equally spaced smaller stand or jet pipes 19 therein for reception of the bottles to be cleansed, and as is customary in similar devices. It is evident that 45 any number of these jets may be provided in keeping with the size of the washing unit and the bottles being cared for. The uppermost central connection of the T 17 is illustrated as being attached to a water supply pipe 20, and the valve 50 21 within this connection 17 is illustrated as having a stem 22 attached thereto and extending upwardly through a suitable hole within a spider like washer 23 installed within the coupling as a guide for said stem. The stem is shown as carry- 55

ing a similar washer like guiding member 24 so that as the valve is reciprocated by the action of the water within the pipes 7 and 20, it may not become dislodged, and provide suitable additional means whereby to rinse the bottles if desired by a different solution from that previously described as coming from the water or steam pipes 2 and 3, it being understood that the pipes 2, 3 and 20 may be provided with any desired form 10 of control valves, not illustrated, and it is deemed non-essential to further describe the type of jet pipes 18, as varieties of such are common in the art.

It will be noted that this fitting 17 is further novel in that it is provided with pressure safety means upon one side of the lower portion thereof, and which comprises a lateral enlargement 28 having an L-shaped passageway therein, opening into the interior of the pipe 7. This passageway has a ball valve and seat therefor as at 29, controlled by the expansive spring 30, regulated as by the screw threaded plunger 31, and which ball may be impinged in a manner to readily exhaust the contents of the pipe 7 by virtue 25 of the valve 2 being suddenly closed, and an undue pressure otherwise exist in the pipe 7.

It will also be apparent that the washing ingredient is forced within the bottles while standing on end, as shown, and will run downwardly 30 out of the bottles and back into the receptacle 9 where the granular material, if any is used, will settle to the bottom thereof as indicated, and where its discharge into the pipes 14 is optionally controlled as previously described. When 35 either steam or water from the pipes 2 or 3 is turned into the standpipe 7, as by the connection 4, previously described, the syphoning action of such, upwardly in the syphon connection 6 will draw granular material through the pipes 14 and force same upwardly into the pipe 7 and discharge it into the bottles being washed, simultaneously, of course, with raising the valve 21 in the connection 17 and shutting off all communication with the pipe 20, thus preventing 40 granular material getting into said pipe above the valve where it might subsequently effect the action of the valve or be forced into the pipes 18 by the action of, for example, clear water coming through the pipe 20 when the valve 21 will automatically be closed by such action.

It is to be noted, and obvious from viewing Figure 3 of the drawings, that the central connection 5 of the valve 4 is preferably of nozzle like shape and extends well within the ejector 55 coupling 6 so as to produce the desired syphoning effect through the branch pipes 13, and that this connection carries that form of valve or cock known as a spigot valve, the spigot being illustrated at 25 and having opposed arcuately shaped ports 26 therein, which, when the spigot is rotated by any form of handle indicated at 27, in one direction, will open communication from the steam pipe 3 to the standpipe 7, but when rotated in the opposite direction will close this 60 communication and open communication with the water pipe 2. When, however, the spigot is left in a neutral position, both of such communications are closed.

Where a considerably larger number of bottles 70 are to be washed simultaneously, it may be found desirable to more evenly distribute the washing

compound or detergent, if such may be used, than is possible with the simple device previously described. For this purpose, I have devised the modification of distributor illustrated in Figures 5 and 6 of the drawings, and which comprises a hollow disc like coupling member 32 having a central conically shaped bottom 33 through opposite walls of which are two opposed branch pipes 34, they discharging in opposite directions within the coupling 32 so as to cause the water 1 to rapidly circulate within said coupling, resulting in the heavier granular particles carried by the water gathering within the central concavity as illustrated at 35 about the base of the cone 33, and into which groove or trough like formation, all of the bottle supporting and washing pipes 36, which extend radially from the coupling, are connected as by the nipples 36', or may be suitably bent for such purpose.

Directly beneath the cone 33 of the coupling 21 32 is formed a hub-like extension 38 of said coupling for the threaded connection with the pipe 39, which, in this instance, is identical with the pipe 7 in the formerly described mechanism.

I have shown the coupling 32 as being provided 25 with a threaded cover 40 having a central threaded connection with a plug installed therein, but, if desired, a second washing or rinsing pipe, similar to that shown at 20, in Figure 1 of the drawings, may be attached, for alternate washing applications to the bottles being thus subjected, and, as illustrated in Figure 6, the radially disposed pipes 36 may be of any desired number and of a length and so disposed that their termini may be in the form of rectangular or circular groups, as desired.

Having thus described my invention, what I claim and desire to secure by Letters Patent, is:

1. A distributing manifold for bottle washing devices characterized by having a circular chamber therein, an axially disposed water and detergent supply connection to the bottom of said chamber, opposed discharge nozzles within said chamber extending from said connection to adjacent the periphery of said chamber where said nozzles discharge at substantially right angles to the axis of the body portion thereof to impart a circular motion to the water and detergent discharged therefrom, and a plurality of radially disposed pipes leading from the bottom of said chamber adjacent said connection each to an object to be cleansed, whereby uniformly mixed water and detergent from said chamber may be discharged through said radially disposed pipes.

2. A distributing manifold for bottle washing devices characterized by having a circular chamber therein, a water and detergent supply connection to said chamber, opposed discharge nozzles within said chamber from said supply connection, the terminal discharge of each of said nozzles being at substantially right angles to the axis of the main body portion thereof and discharging in an opposite direction to that of the other nozzle so as to impart a circular motion to the discharge therefrom and cause the water and detergent to uniformly circulate within said chamber, and a plurality of pipes each leading from said chamber to an object to be cleansed.
